DRAPEY SLIDE FOR A CURTAIN ROD

Samuel Galiotti, 1360 NE. 204th Terrace,
North Miami Beach, Fla. 33162

Filed June 29, 1973, Ser. No. 375,090

Term of patent 14 years

Int. Cl. D8—08

U.S. Cl. D8—239

FIG. 1

FIG. 2

FIG. 3

FIG. 4

FIG. 5

FIG. 1 is a top plan view of a drapery slide for a curtain rod in accordance with my new design;

FIG. 2 is an elevational view of one side of the drapery slide;

FIG. 3 is an elevational view of one end of the drapery slide;

FIG. 4 is an elevational view of the opposite side of the drapery slide; and

FIG. 5 is a bottom plan view thereof.

I claim:

The ornamental design for a drapery slide for a curtain rod, as shown.
